UNITED STATES PATENT OFFICE.

LESLIE R. McDONALD, OF MONTREAL, QUEBEC, CANADA.

DISPLAY APPARATUS.

Application filed March 17, 1923. Serial No. 625,923.

To all whom it may concern:

Be it known that I, LESLIE R. McDONALD, a citizen of the United States, residing at Montreal, Quebec, Canada, have invented 5 certain new and useful Improvements in Display Apparatus, of which the following is a specification.

My invention relates to that class of display apparatuses wherein a considerable 10 number of flexible placards are wound around a rotatable holder and are allowed to successively unroll and drop into view position as the holder revolves, step by step; and my improvements are particularly directed 15 to the means whereby the placards are successively released and caused to assume the proper view position, and to details of construction in the holder and its rotating mechanism, as will be hereinafter more fully 20 explained.

In the drawings, Fig. 1 is a top view of my improved apparatus, the case being removed; Fig. 2 is a back elevation, the back 25 of the case being removed and portions of the lower part of the apparatus being broken away to condense the figure; Fig. 3 is a view, of the spindle and placard holding elements, partly in section; Fig. 4 is an end view on an enlarged scale, taken as looking toward 30 the left on Fig. 2, the carrier rotating elements being omitted for clearness; Fig. 5 is a view, on a still further enlarged scale, taken on the line 5—5 of Fig. 2, looking toward the left; Fig. 6 is a detail, taken on 35 the line 6—6 of Fig. 5, looking down, the section line 6—6 being at right angles to the line 5—5 of Fig. 2; Fig. 7 is a detail, on the same scale as Fig. 4, illustrating the relative positions on their carrying shaft 40 of the elements for holding and releasing the ends of the placards; Fig. 8 is a detail, on the same scale as Fig. 5, showing the relative positions on their carrying shaft of the feed governing cams; and Fig. 9 is 45 a detail, on an enlarged scale, of a modification of the top of a supporting standard.

Similar reference numerals designate similar parts in all the figures.

The apparatus is preferably assembled in 50 a suitable case 1, provided with a usual open, or glass covered front, which is omitted in the drawings as being well understood in the art. The parts are carried by suitable standards, as 2, 3, preferably forked as in-

dicated by the broken line 7—7 in Fig. 4, 55 so that the spindle 8, carrying with it the various elements centered around it, may conveniently be lowered into the forks in mounting the placard carrier, in which position it may be secured by tightening bolts 60 as 9, 9, which pass through the normally stationary elements centered around the shaft, and through clamping plates 10 and 11.

The spindle 8 carries not only the disks 15, 15 which are peripherally slotted to receive the ends of the placard carrying bars and the keeper disks 16, 17, but also intermediate disks 18, 19, 21, which are conveniently spaced to support the placard carrying bars, one of which is indicated by 22, 70 in Fig. 3, so that the bars will not become bent out of proper position or displaced in the usual operation of the apparatus.

The keyhole slot 20 in the keeper disk 16, 75 permits the introduction of the placard carrying bars, one by one, into their proper positions in the slots in disks 15, 15, the rotation of the disk 16 relative to the disk 15 serving to lock the ends of the bars in position under the flange of the disk 16. 80

A motor 25, through a worm 26 on its shaft 27, rotates a worm gear wheel 28 mounted on shaft 29, upon the inner end of which is journaled frictionally a pawl arm 30, the detent 31 of which engages with the teeth 32, 32 on the keeper disk 16, and is normally pressed up against the same by the rotation of the shaft 29. The shaft 29 85 also carries an eccentric 33, upon which is mounted the feeding pawl 34, which is reciprocated by the rotation of the eccentric, so that its detent 35 will engage with the teeth 32 and turn the carrier one tooth for each revolution of the shaft 29. The detent 31 extends over the arm 34, which acts as 90 a keeper to prevent its dropping out of operative position, if the frictional resistance produced by the spring washer 36 should be insufficient to hold the arm to duty. 95

The shaft 29 has a pair of disks 40, 41, so 100 secured as to turn with the shaft; and between them is an eccentric 42, which is secured to turn with the disks, as by a pin 43; and around the eccentric and between the disks is mounted one end of an arm 45, so 105 that the rotation of the shaft 29 raises and lowers the arm 45, which is preferably extensible and made with a terminal portion

46, which is adjustably secured to the arm 45, as by bolts 47, 47 passing through its slot 48. The arm 45 is provided with a counterweight 49 or other suitable means to cause it normally to incline away from the placard carrier.

The upper end of the terminal 46 is provided with two fingers 50 and 51, the finger 50 having two recesses in its inner side these fingers constituting a toothed clutch; and into the opening between the fingers extend four pins 52, 52, which project laterally between disks 53, 58 forming a pinion keyed to a shaft 54, which is journaled between arms 55, 56, carried by the supports 2 and 3, the spindle 8 passing through them, so radial adjustment of the shaft 54, relative to the placard carrier, is permitted and may be governed by a stud 57 adjustably mounted in a slot in the arm 55.

This shaft 54 carries placard holding and releasing elements 60, 61, which are adapted to press against the roll of placards, and to release the end of one placard with each quarter revolution of the shaft 54.

When, therefore, the arm 45 is drawn down by the turning of the shaft 29 from the position shown in Fig. 5, it will give the shaft 54 a quarter turn, the pins between the disks 53 and 58 permitting this movement but preventing retrograde movement. This turning of the shaft 54 produces a corresponding quarter turn of the elements 60, 61, which alternately release the notched ends of placards which are so adjusted that the end of one placard is freed with each quarter turn of the shaft 54.

Upon the shaft 29 is mounted a cam 70, which travels beneath and rocks an arm 71, of a bell crank 71, 72 journaled on the shaft 8. The arm 72 carries a rod 73, upon which are mounted two pawl arms 74, 75, each having a thin blade 76 projecting from its under side. The pawl 74 carries an arm 77, preferably of spring metal; and the pawl 75 has a similar arm 78. These arms 77 and 78, respectively, lie over and against cam arms 79 and 80, which are mounted at right angles to each other upon the shaft 54.

Consequently, when the bell crank 71, 72 is rocked by the cam 70, the pawls 74, 75 will be swung forward and back around the roll of placards; and on the forward stroke one of them will be held up out of contact with the placard roll by its arm 77 or 78 being raised by its cooperating cam arm 79 or 80; while the other pawl will press against the placard roll, and its blade 76 will slip under the edge of the placard which has been released by the appropriate holding cam 60 or 61. The continued forward movement of the pawl will push the end of the released placard forward, allowing the air to flow in beneath it, and overcoming any

tendency which may exist for it to hang to the roll of placards, so that the placard will immediately release itself from the roll and drop down into view position.

It will be understood that the relative adjustments of the apparatus are such that the step by step rotation of the placard carrier releases the placard ends one by one from the control of the cams 60, 61, which turn in the opposite direction from the placard carrier, thus keeping the ends of the placards snugged up around the roll, and that the throw of the pawls 74, 75 is timed to push forward and free from the roll the ends of the placards successively released.

A bar 90, adjustable radially of the placard roll by means of having its ends carried in slots in arms 91, 92 which are centered around spindle 8, and supported by standards 1 and 2, through suitable means, as studs 93, 93 and bolts 94, 94, carries expanded roll keepers 95, 95, which curve around the placard roll below the releasing mechanism, and act to keep the body of placards rolled and to reroll those which have been released, as the carrier revolves.

In the primary form illustrated for the supports 2 and 3 they are shown as being forked at their upper ends, so that the placard carrier and its associated parts may be lifted radically out of the supports. In some forms of assembling it is preferable, however, to be able to remove the carrier from the supports in a different direction. In Fig. 9 is illustrated the upper end of a supporting standard, in which the fork is disposed at a laterally inclined angle, so that the spindle and its associated parts may be removed laterally from the standard if that is desirable.

By means of my improvements I secure a display apparatus in which the important elements which require relative adjustment are centered around a common axis, and may be removed from or placed in position in their supporting means as a unitary assembly, thus greatly facilitating the arrangement and rearrangement of placards, and the relative adjustment of the parts of the apparatus.

Also, in this apparatus the normal effect of the placard releasing mechanism is to keep the placards snugly rolled up until the time arrives for releasing each one of them, when, not only is the end of the placard freed from the detaining mechanism, but it is also positively and mechanically pushed forward so as to cause the placard to unroll and to drop into new position.

It will be understood that the form of apparatus shown is to be taken as a preferred type, but not as an exclusive one. For it is evident that details of construction may be modified, as by the use of mechanical equivalents, without departing from the spirit and

scope of my invention as described and claimed.

Having thus described my invention, what I claim and desire to secure by Letters 5 Patent of the United States is:

1. In a display apparatus, the combination of a rotatable placard carrier, a series of flexible placards each carried by one end thereby and adapted to be rolled in close 10 contact with each other around the carrier, the free ends of the placards being of substantially the normal thickness thereof, and mechanical means for engaging with and successively separating the free ends of 15 the placards.

2. In a display apparatus, the combination of a rotatable placard carrier, a series of flexible placards each carried by one end thereby and adapted to be rolled in close 20 contact with each other around the carrier, the free ends of the placards being of substantially the normal thickness thereof, and mechanical means for engaging with and successively separating the free 25 ends of the placards.

3. In a display apparatus, the combination of a rotatable placard carrier, a series of flexible placards each carried by one end thereby, and adapted to be rolled in close 30 contact with each other around the carrier, the free ends of the placards being of substantially the normal thickness thereof, and mechanical means for engaging and successively separating and pushing forward the 35 free ends of the placards.

4. In a display apparatus, the combination of a rotatable placard carrier, a series of flexible placards rolled around the carrier and each having a free end of substantially 40 the normal thickness of the placard, means for releasing the free ends of the placards one by one, and mechanical means for successively engaging beneath and separating the free ends of the placards from the roll.

5. In a display apparatus, the combination of a rotatable placard carrier, a series of flexible placards rolled around the carrier and each having a free end, means for releasing the free ends of the placards one by one, and reciprocating means for engaging with and successively separating the 50 free ends of the placards from the roll.

6. In a display apparatus, the combination of a rotatable placard carrier, a series of flexible placards rolled around the carrier and each secured thereto by one end, carrier rotating means, means for releasing the free ends of the placards successively, and mechanical means actuated by the carrier rotating means, for engaging beneath and separating said free ends as released from the roll of placards.

7. In a display apparatus, the combination of a rotatable placard carrier, a series 55 of flexible placards rolled around the car-

rier and each secured thereto by one end, carrier rotating means, means for releasing the free ends of the placards successively, and mechanical means, actuated by the carrier rotating means and embodying pushing 70 pawls, for separating said free ends as released from the roll of placards.

8. In a display apparatus, the combination of a rotatable placard carrier, a series of flexible placards rolled around the carrier 75 and each secured thereto by one end, carrier rotating means, means for releasing the free ends of the placards successively, and means, embodying alternately acting pawls, for separating said free ends as released from the roll of placards.

9. In a display apparatus, the combination of a rotatable placard carrier, a series of flexible placards rolled around the carrier and each secured thereto by one end, 85 carrier rotating means, means for releasing the free ends of the placards successively, and means, embodying alternately acting pawls governed by the releasing actuating means, for separating said free ends as released from the roll of placards.

10. In a display apparatus, the combination of a rotatable placard carrier, a series of flexible placards rolled around the carrier and each secured thereto by one end, 95 carrier rotating means, means for releasing the free ends of the placards successively, and means, embodying a pair of alternately acting pawls, for separating said free ends as released from the roll of placards.

11. In a display apparatus, the combination of a rotatable placard carrier, a series of flexible placards rolled around the carrier and each secured thereto by one end, carrier rotating means, means for releasing the free ends of the placards successively, 105 and means, embodying alternately acting pawls, for separating said free ends as released from the roll of placards, and means embodying a bell crank for actuating the said pawls.

12. In a display apparatus, the combination of a rotatable placard carrier, a series of flexible placards rolled around the carrier and each secured thereto by one end, 115 carrier rotating means, means for releasing the free ends of the placards successively, and means, embodying alternately acting pawls, for separating said free ends as released from the roll of placards, and means embodying a bell crank and an actuating cam for actuating the said pawls.

13. In a display apparatus, the combination of a rotatable placard carrier, a series of flexible placards rolled around the carrier and each secured thereto by one end, carrier rotating means, step by step operating means for releasing the free ends of the placards successively, and means, embodying alternately acting pawls, acting in uni- 125

son with the releasing means, for separating said free ends as released from the roll of placards.

14. In a display apparatus, the combination of a rotatable placard carrier, a series of placards each carried by one end thereby and wound thereabout, step by step rotating means for releasing the free ends of the placards one by one, and reciprocating means moving in synchronism with the releasing means for separating the freed ends of the placards from the roll.

15. In a display apparatus, the combination of a rotatable placard carrier, a series of flexible placards each attached by one end to and wound around the carrier, and having free ends of substantially the same thickness as the placard, carrier rotating means, and intermittently rotatable means, for releasing the free ends of the placards successively.

16. In a display apparatus, the combination of a rotatable placard carrier, flexible placards rolled on the carrier, and having free ends of substantially the same thickness as the placard, and intermittently rotatable means for releasing the free ends of the placards one by one.

17. In a display apparatus, the combination of a rotatable placard carrier, flexible placards rolled on the carrier, and having free ends of substantially the same thickness as the placard, carrier rotating means, rotatable means, for releasing the free ends of the placards one by one, and means for actuating the rotatable means step by step.

18. In a display apparatus, the combination of a rotatable placard carrier, flexible placards rolled on the carrier, and having free ends of substantially the same thickness as the placard, rotatable means for releasing the free ends of the placards one by one, and reciprocating means for actuating the rotatable means step by step.

19. In a display apparatus, the combination of a rotatable placard carrier, flexible placards rolled on the carrier and rotatable means, embodying a plurality of alternately operating placard gripping elements, for releasing the free ends of the placards one by one, and reciprocating means for actuating the rotatable means step by step and for preventing reverse movement thereof.

20. In a display apparatus, the combination of a rotatable placard carrier, flexible placards rolled on the carrier, and rotatable means, embodying a plurality of alternately operating placard gripping elements, for releasing the free ends of the placards one by one, and reciprocating and oscillating means for actuating the rotatable means step by step and for preventing reverse movement thereof.

21. In a display apparatus, the combination of a rotatable placard carrier, flexible

placards rolled on the carrier, and rotatable means, embodying a plurality of alternately operating placard gripping elements, for releasing the free ends of the placards one by one, and extensible reciprocating means for actuating the rotatable means step by step and for preventing reverse movement thereof.

22. In a display apparatus, the combination of a rotatable placard carrier, flexible placards rolled on the carrier, and rotatable means, embodying a plurality of alternately operating placard gripping elements, for releasing the free ends of the placards one by one, and reciprocating means embodying a forked arm, for actuating the rotatable means step by step and for preventing reverse movement thereof.

23. In a display apparatus, the combination of a rotatable placard carrier, flexible placards rolled on the carrier, and rotatable means, embodying a plurality of alternately operating placard gripping elements, for releasing the free ends of the placards one by one, and reciprocating means embodying a toothed clutch, for actuating the rotatable means step by step and for preventing reverse movement thereof.

24. In a display apparatus, the combination of a rotatable placard carrier, flexible placards rolled on the carrier, and rotatable means, embodying a plurality of alternately operating placard gripping elements, for releasing the free ends of the placards one by one, and reciprocating means embodying a reciprocating, unitary, propelling and holding element cooperating with a pinion for actuating the rotatable means step by step and for preventing reverse movement thereof.

25. In a display apparatus, the combination, with a rotatable placard carrier, of means for rotating the carrier step by step, embodying a ratchet wheel and a retractable, cam-actuated pawl arm provided with a tooth laterally projecting therefrom in one direction and a detent cooperating pawl provided with a tooth laterally projecting therefrom in the opposite direction.

26. In a display apparatus, the combination, with a rotatable placard carrier, of means for rotating the carrier step by step, embodying a ratchet wheel and a retractable, cam-actuated pawl arm provided with a laterally projecting tooth and a detent pawl provided with a tooth laterally projecting therefrom across the cam-actuated pawl arm.

27. In a display apparatus, the combination, with a rotatable placard carrier, of means for rotating the carrier step by step, embodying a ratchet wheel, a rotating shaft provided with an eccentric cam, a retractable and projectable pawl arm carried by said cam and provided with a laterally pro-

jecting tooth, a detent pawl mounted on said shaft and provided with a tooth projecting laterally in a direction opposite to the first mentioned tooth, and frictional means for 5 coordinating the movements of the said pawl arm and detent pawl.

28. In a display apparatus, the combination of a rotatable placard carrier provided with a series of flexible placards each attached thereto by one end and rolled thereupon, intermittently rotatable means for releasing the free ends of the placards one 10 by one, and intermittently operable mechanical means for definitely separating each freed end from the roll as released, means for rotating the placard carrier step 15

by step, and common means for actuating the said carrier rotating means, releasing means and separating means.

29. In a display apparatus, the combination of a rotatable placard carrier provided with a series of flexible placards each attached thereto by one end and rolled thereupon, intermittently rotatable means for releasing the free ends of the placards 25 one by one, reciprocating means for definitely separating each freed end from the roll as released, means for rotating the placard carrier step by step, and common means, for actuating the said carrier rotating means, 30 releasing means and separating means.

LESLIE R. McDONALD.
